UNITED STATES PATENT OFFICE.

EUGENE McCLELLAN SCOVILLE, OF WAIPAHU, TERRITORY OF HAWAII.

PLANI-METER.

No. 844,195.

Specification of Letters Patent.

Patented Feb. 12, 1907.

Application filed February 16, 1906. Serial No. 301,371.

To all whom it may concern:

Be it known that I, EUGENE McCLELLAN SCOVILLE, a citizen of the United States, and resident of Waipahu, Oahu, Hawaii, have invented a new and Improved Planimeter, of which the following is a full, clear, and exact description.

My invention relates to a planimeter adapted to perform the usual functions of instruments of this character.

The principal objects of the invention are to decrease the expense of construction and the number of parts of instruments of this character, to provide for additional smoothness, and to provide means for supporting a number of scales in a convenient position in such a manner that it will not be necessary to replace the scales in operation.

Other features of the invention will appear below.

Reference is to be had to the accompanying drawings, forming a part of this specification, in which similar characters of reference indicate corresponding parts in all the figures.

Figure 1 is a plan of a planimeter constructed in accordance with the principles of my invention. Fig. 2 is a plan view of the same, partly in section. Fig. 3 is a sectional view on the line 3 3 of Fig. 2. Fig. 4 is a sectional view on the line 4 4 of Fig. 3. Fig. 5 is a sectional view on the line 5 5 of Fig. 2, and Fig. 6 is a sectional view on the line 6 6 of Fig. 5.

My present invention belongs to that type of planimeters in which a track 10 is employed for guiding a certain part of the device. I have shown this track as being fixed to the base or table on which the instrument operates and being provided with an end 11, extending over the surface of the base or table sufficiently near thereto to provide for holding an indicator-card 12 in proper position for operation. The main reason for having the track project over the indicator-card is to allow for the operation of the device on a particularly short card and also to provide a convenient manner for holding the card. As will be readily observed, the card is held by being placed under the end 11 of the track, which is preferably provided with teeth or corrugations 13 for assisting in holding the cards.

The instrument itself comprises a frame

14, which is provided with a swiveled member 15, having downwardly-projecting sides 16. Through these sides extend a pair of screws 18^a, which obviously can be adjusted to any desired distance from each other, and which are provided with points for entering 60 depressions in the sides of a caster 18^b. This caster is provided with a beveled groove 19^b for running on the track 10, which is also provided with beveled sides to prevent accidental displacement of the caster. The sides 65 16 terminate in points 17, extending below the lower surface of the caster and below the top of the track. These are provided for the purpose of locating a line on the indicator-card and affording a guide as to the point at 70 which the instrument is originally set up. The frame 14 is provided with two pairs of collars 18, which extend inwardly through hubs 19 on the frame. These collars are located on the inner side of a pair of projections 20, with which the frame is provided. On the outside of these projections is a second pair of collars 21, which are threaded into the collar projections and are therefore 75 adjustable in such a manner as to provide for 80 regulating the pressure of ball-bearings 22 on a sliding shaft 23, running through these two sets of bearings. This shaft is provided with a head 24 and with a mark 25 for indicating the starting-point of the instrument. 85 On the opposite end of this shaft is a knife-edged wheel 26. The collars 18 are provided with slots 27, into which are passed a series 90 of scales 28. In the present instance I have shown four of these slots on each collar, and consequently four scale members are adapted 95 to be located on the instrument, each scale member being provided with two scales, one on each side. These scales are employed in the usual manner, and as the collars 18 are not provided with screw-threads they can be turned so as to bring any desired one of the scales into proper position to read the mean effective pressure directly thereon. Through the frame at right angles 100 to the shaft 23 extends a second shaft 29, which is provided with a tracing-point 30. A thumb-screw 31 is provided for securing this shaft in any desired position on the frame.

In operation the card bearing the diagram 105 is inserted under the clip 11, and the machine is set with the caster in such position that the points 17 are at one end of the dia-

- gram, and the arm 29 is adjusted to bring the tracing-point at the other end. The proper scale is brought into position, the scales being graduated generally to correspond with the scales of the springs with which the indicator-card is taken, and the instrument is placed on the track with the tracing-point at any suitable place on the diagram. The shaft 23 is then moved into a position such that the mark 25 thereon corresponds to the zero-mark of the scale. The tracing-point is now passed over the outline of the diagram until it is returned to its starting-place, the tracing-wheel being carefully retained in contact with the base or table. The wheel rotates during lateral movement of the shaft, and the shaft moves through its bearing during lateral movement of the arm 29, and the position of the mark 25 with reference to the scale at the completion of the movement of the tracing-point indicates the mean effective pressure of the engine when used on indicator-cards or the area of the surface inclosed by the tracing of the point. It will be understood that when merely the area is desired scales graduated in square measures would be used.

Having thus described my invention, I claim as new and desire to secure by Letters Patent—

1. A planimeter comprising a frame, a shaft movable through the frame and provided with a tracing-wheel, and means on the frame for detachably supporting a plurality of scales longitudinally of the shaft and with their edges adjacent thereto and in spaced relation with respect to each other.

2. In a planimeter, the combination with a frame, of a pair of rotatable collars thereon, a shaft movable through the collars and a plurality of scales held by said collars, said frame having bearings and the collars having bearing-surfaces adjacent to said bearings.

3. In a planimeter, the combination of a frame having a pair of projections provided with passages therethrough in alinement with each other, and a pair of collars, one on the inside of each of the said projections extending into the passages, said collars having slots for receiving scales between them.

4. In a planimeter, the combination of a frame having a pair of projections provided with passages therethrough in alinement with each other, a pair of collars, one on the inside of each of the said projections extending into the passages, said collars having slots for receiving scales between them, a pair of collars located on the outside of said projections, said last-named collars having screw-threaded extensions located in said passages for permitting adjustment of the collars, a shaft passing through the several collars and

having a registering-mark, and ball-bearings located between the adjacent ends of the inside and outside collars.

5. In a planimeter, the combination of a frame having adjustable bearings, a shaft passing through said bearings, a knife-edged wheel secured to the shaft, an adjustable bar at right angles to said shaft, and a tracing-point on the bar.

6. In a planimeter, the combination of a frame having adjustable bearings, a shaft passing through said bearings, a knife-edged wheel secured to the shaft, an adjustable bar at right angles to said shaft, a tracing-point on the bar, a caster swiveled to the frame, and means for adjusting the caster.

7. In a planimeter, the combination with a frame of a shaft mounted for rotation and longitudinal movement thereon, a knife-edged wheel thereon, a bar on the frame at right angles to said shaft and longitudinally movable, and a member swiveled to turn on an axis at right angles to the shaft and to the bar, said member having a pointer, and a caster rotatably mounted on said member and located with its axis in a vertical plane passing through the pointer.

8. A planimeter having a swiveled member, a pair of pointers extending downwardly therefrom, a pair of pointed screws adjustably mounted in said members, their points extending inwardly toward each other, and a caster having depressions for receiving said points and located between said pointers, the extremities of said pointers being below the bottom of the caster and vertically below the adjustable points.

9. In a planimeter, the combination with a frame of a shaft mounted for rotation and longitudinal movement thereon, a knife-edged wheel thereon, a bar on the frame at right angles to said shaft and longitudinally movable, a member swiveled to turn on an axis at right angles to the shaft and to the bar, said member having a pointer, and a caster rotatably mounted on said member and located with its axis in a vertical plane passing through the pointer, and a track on which the caster is adapted to run, said track having means for holding an indicator-card.

10. The combination of a planimeter having a swiveled caster, and a track upon which said caster is adapted to run, said track having a clip for receiving and holding an indicator-card.

In testimony whereof I have signed my name to this specification in the presence of two subscribing witnesses.

EUGENE McCLELLAN SCOVILLE.
